Inventor.

Gustav L. Jager

UNITED STATES PATENT OFFICE.

GUSTAV L. JAEGER, OF NEW YORK, N. Y.

DESIGN FOR A HAT-BOX.

Specification forming part of Design No. 3,386, dated February 23, 1869.

To all whom it may concern:

Be it known that I, GUSTAV L. JAEGER, of the city, county, and State of New York, have invented a new and original Design for a Hat-Box; and I do hereby declare the following to be a full, clear, and exact description thereof, which will enable those skilled in the art to make and use the same, reference being had to the accompanying drawing, forming part of this specification.

The drawing represents a side elevation of my hat-box.

This invention relates to a design for a hat-box, the body A of which is provided with a

series of corrugations, a, whereby an ornamental and distinguishing appearance is given to my box. The upper part of the body A forms a shoulder, b, and a vertical flange, c.

Having thus described my invention, what I claim as new, and desire to secure by Letters Patent, is—

The design for a hat-box, as shown and described.

GUSTAV L. JAEGER.
